CLAIM

The ornamental design for a lower air grille, as shown and described.

DESCRIPTION

FIG. 1 is a front perspective view of a lower air grille showing our new design;

FIG. 2 is a front view thereof;

FIG. 3 is a rear view thereof;

FIG. 4 is a side view thereof;

FIG. 5 is a top plan view thereof; and,

FIG. 6 is a bottom view thereof.

It will be understood that the broken lines shown in the drawings illustrate portions of the lower air grille that form no part of the claimed design.
